BUFFER FOR RAILWAY CARS

John W. Marsh, Alexandria, Va., assignor of one-fourth to Florence E. Marsh, one-fourth to Marianne Marsh, and one-fourth to Mary Marsh, all of Alexandria, Va.

Application November 25, 1944, Serial No. 565,122

5 Claims. (Cl. 213—221)

1

This invention relates to buffers for railway cars of the type shown in my co-pending application filed November 9, 1944, Serial Number 562,655, and is concerned more particularly with a novel buffer which is an improvement on that shown in the application referred to.

The objects and advantages of the present invention will become apparent upon a consideration of the following detailed description when taken in conjunction with the attached drawings, in which

Fig. 1 is a sectional view of a buffer construction embodying the elements of the present invention. The upper portion of this figure is taken along the line 1—1 of Fig. 2, and the lower portion along the line 6—6 of Fig. 2.

Fig. 2 is a sectional view, the left portion of which is taken along the line 2—2 of Fig. 1, and the right portion of which is taken along the line 7—7 of Fig. 1.

Fig. 3 is a side view of the buffer lock.

Fig. 4 is an end view of the buffer lock.

Referring to the drawings it will be seen that there is provided a cylindrical housing 1, on one end of which is a flange portion 2 suitable for attachment to the frame of a railway vehicle. The flanged end is partially closed, the closure being provided with an opening 3 of non-circular outline. The open end of the housing has inwardly projecting lips 4, 5, 6, 7 formed thereon and spaced uniformly around the inner periphery of the housing, and extending over less than half of said inner periphery leaving spaces 8, 9, 10, 11 therebetween.

The buffer includes a plunger, which is provided at its outer end with a buffering head 12, attached to a cylindrical portion 13, which is adapted to oscillate within the inner peripheries of lips 4, 5, 6, 7. The inner end of cylindrical portion 13 is provided with outwardly projecting sectors as 14, 15, 16, spaced uniformly around the periphery and adapted to oscillate within the cylindrical housing 1, and within spaces 8, 9, 10, 11.

A buffer lock 18, shown in more detail in Figs. 3, 4, is mounted within the housing 1 and it is provided with a base 19 having an inner surface 20 suitable for engaging spring 24, and an outer surface 21 suitable for engaging the inner surface of the closed end of the housing. Base 19 is provided with a projection 17, which is of a non-circular outline corresponding to that of opening 3 and is adapted to be received in that opening to hold the lock against rotational movement within the housing. Buffer lock 18 is also provided with means cooperating with means on the

2

cylindrical portion 13 of the plunger to hold the lock and plunger against relative rotational movement while permitting relative axial movement thereof. In the construction illustrated, such means on the lock take the form of keys 22, 23, and the means on the plunger are walls of the projecting sectors 14, 15, and 16.

A spring 24 is positioned within cylindrical portion 13, abutting buffer head 12 and the inner surface 20 of lock 18, in a manner as to continually urge the buffer plunger outwardly of housing 1 and retain surface 21 in contact with the inner surface of the housing closure. The central portion of the spring 24 is shown broken away in Fig. 1 to more clearly show the construction of outwardly flaring sector 15.

The assembly of the buffer is accomplished by inserting buffer lock 18 in housing 1, base 19 passing within the inner periphery of lips 4, 5, 6, 7, and keys 22, 23 passing through openings 9, 11 between lips 4, 5, and 6, 7. Buffer lock 18 is then rotated within housing 1 until the projection 17 is angularly displaced from registry with opening 3, while keys 22, 23 are aligned with diametrically opposite lips 4, 6 or 5, 7. Spring 24 is then inserted, abutting the inner surface 20 of base 19. The outwardly projecting sectors as 14, 15, 16 are passed between lips 4, 5, 6, 7 and keys 22, 23 enter the spaces between diametrically opposite sectors. Axial movement of the buffer plunger is continued toward the base closure of housing 1, compressing spring 24 until the outwardly projecting sectors as 14, 15, 16 pass lips 4, 5, 6, 7, whereupon the cylindrical portion 13 is rotated within housing 1, rotating lock 18 with it, until projection 17 registers with opening 3 and enters that opening under the pressure of the spring. In this position of the housing, the sectors 14, etc. are aligned with lips 4, etc. and further rotation of the housing is prevented by engagement of projection 17 within opening 3, such engagement being retained by the axial force of spring 24.

Disassembly of the buffer is accomplished by forcing lock 18 towards buffer face 12, against axial pressure of spring 24 until projection 17 is disengaged from opening 3. The buffer plunger and lock are then rotated within housing 1 until the outwardly projecting sectors as 14, 15, 16 are aligned with the spaces as 8, 9, 10, 11 between lips 4, 5, 6, 7, whereupon the buffer plunger and spring can be removed axially. Rotation of lock 18 within housing 1 until keys 22, 23 are aligned with spaces, such as 8, 9, 10, 11, between lips 4, 5, 6, 7 permits the removal of lock 18 axially from housing 1.

It will be apparent that projection 17 and opening 3 may be of any size or shape within the physical limits of housing 1 and lock 18, provided rotation of these parts relative to each other is prevented by their mutual engagement. It will also be apparent that the projection may be formed on the housing closure and the opening on the lock, or that the opening in either position may be merely a recess, without departing from the spirit of this invention. Moreover, that a greater or less number of keys may be used on the lock, and the keys may engage the outwardly projecting portions of the plunger either between the portions as shown, or within the portions as shown and described in my co-pending application Serial No. 562,655.

These and other modifications of my invention will suggest themselves to one skilled in the art. The embodiments shown and the embodiments claimed are therefore to be considered in all respects as illustrative and not restrictive, and all changes that come within the means and range of equivalency of the embodiments shown and the embodiments claimed are therefore intended to be embraced therein.

Having described my invention, what I claim is new and wish to secure by Letters Patent is:

1. A buffer comprising a housing having one end open and the other substantially closed and also having circumferentially spaced inward projections at its outer end, a hollow plunger extending into the housing through its open end and adapted to be moved axially relative to the housing, the exposed end of the plunger being substantially closed and the plunger having circumferentially spaced outward projections lying within the housing and engageable behind the housing projections to limit the outward movement of the plunger from the housing, the projections on the plunger being adapted, upon partial relative rotation of the housing and plunger, to be passed between the housing projections, the housing having an opening of non-circular outline in its closed end, the opening having side walls extending substantially parallel to the longitudinal axis of the housing, a lock member within the housing having a projection received within said opening, the side surfaces of said projection extending substantially parallel to and engaging corresponding side walls of said opening to hold the lock member and housing against relative rotation, the lock member and plunger having interengaging means preventing relative rotation of the lock member and plunger while permitting their relative longitudinal movement, and spring means within the plunger and housing acting on the closed end of the plunger and on the lock member to maintain the projection on the lock member in said opening in the closed end of the housing.

2. A buffer comprising a housing having one end open and the other substantially closed and also having circumferentially spaced inward projections at its outer end, a hollow plunger extending into the housing through its open end and adapted to be moved axially relative to the housing, the exposed end of the plunger being substantially closed and the plunger having circumferentially spaced outward projections lying within the housing and engageable behind the housing projections to limit the outward movement of the plunger from the housing, the projections on the plunger being adapted, upon partial relative rotation of the housing and plunger, to be passed between the housing projections,

the housing having an opening of non-circular outline extending through its closed end, a lock member within the housing having a projection of non-circular outline received within said opening and engaging the walls thereof to hold the lock member and housing against relative rotation, the lock member having portions engageable with the plunger projections to prevent relative rotation of the lock member and plunger while permitting their relative longitudinal movement, and spring means within the plunger and housing acting on the closed end of the plunger and on the lock member to maintain the projection on the lock member within said opening in the closed end of the housing.

3. A buffer comprising a housing having one end open and the other substantially closed and also having circumferentially spaced inward projections at its outer end, a hollow plunger extending into the housing through its open end and adapted to be moved axially relative to the housing, the exposed end of the plunger being substantially closed and the plunger having circumferentially spaced outward projections lying within the housing and engageable behind the housing projections to limit the outward movement of the plunger from the housing, the projections on the plunger being adapted, upon partial relative rotation of the housing and plunger, to be passed between the housing projections, the housing having an opening of non-circular outline extending through its closed end, the opening having side walls extending substantially parallel to the longitudinal axis of the housing, a lock member within the housing having a projection received within said opening, the side surfaces of said projection extending substantially parallel to and engaging corresponding side walls of said opening to hold the lock member and housing against relative rotation, the lock member having key means engageable with the projections on the plunger to prevent relative rotation of the plunger and lock member while permitting their relative longitudinal movement, and spring means within the plunger and housing acting on the closed end of the plunger and on the lock member to maintain the projection on the lock member within said opening in the closed end of the housing.

4. A buffer comprising a housing having one end substantially closed and provided at its open end with circumferentially spaced inward projections, a hollow plunger mounted in the housing for sliding movement within the projections and having a portion extending out of the housing, the exposed end of the plunger being closed, the portion of the plunger within the housing having circumferentially spaced outward projections behind and aligned with the projections on the housing, the projections on the plunger being adapted, upon relative rotation of the housing and plunger, to be passed between the projections on the housing, a lock member within the housing, the lock member and plunger each having means positively engaging the other to prevent relative angular movement of the plunger and member while permitting their relative axial movement, interengaging means on the lock member and on the housing adjacent its closed end operable to prevent relative rotation of the lock member and housing, and spring means within the housing and plunger engaging at one end the closed outer end of the plunger and, at the other end, a portion of the lock member, said spring means acting to hold the interengaging

means on the lock member and housing in operative relation, whereby the projections on the plunger are maintained in alignment with those on the housing.

5. A buffer comprising a housing having one end substantially closed and provided at its open end with circumferentially spaced inward projections, a hollow plunger mounted in the housing for sliding movement within the projections and having a portion extending out of the housing, the exposed end of the plunger being closed, the portion of the plunger within the housing having circumferentially spaced outward projections behind and aligned with the projections on the housing, the projections on the plunger being adapted, upon relative rotation of the housing and plunger, to be passed between the projections on the housing, a lock member within the hous-

ing having an end portion seated against the closed end of the housing, the lock member and plunger having interengaging means preventing relative angular movement of the lock member and plunger while permitting their relative axial movement, means on the lock member and on the housing adjacent its closed end positively engaging one another to prevent relative rotation of the lock member and housing, and spring means within the housing and plunger confined between the closed outer end of the plunger and the end portion of the lock member, said spring means acting to hold the interengaging means on the lock member and housing in operative relation, whereby the projections on the plunger are maintained in alignment with those on the housing.

JOHN W. MARSH.
